Attorney

UNITED STATES PATENT OFFICE.

EDWARD C. ROSS, OF WOLCOTT, INDIANA.

TRUNK.

Specification of Letters Patent.

Patented Jan. 2, 1917.

Application filed July 15, 1916. Serial No. 109,520.

To all whom it may concern:

Be it known that I, EDWARD C. Ross, a citizen of the United States, residing at Wolcott, in the county of White and State 5 of Indiana, have invented certain new and useful Improvements in Trunks, of which the following is a specification, reference being had to the accompanying drawings.

This invention relates to certain improvements in trunks and has relation more particularly to a device of this general character especially designed and adapted for use in connection with automobile tires or the like; and it is an object of the invention to provide a trunk of this general character wherein a side face is open and wherein novel and improved means is employed for closing said open face.

It is also an object of the invention to 20 provide a novel and improved trunk of this general character wherein an annular chamber is afforded for a tire and wherein the central portion is divided into compartments to receive miscellaneous objects such 25 as inner tubes, tools or other objects.

The invention consists in the details of construction and in the combination and arrangement of the several parts of my improved trunk whereby certain important advantages 30 are attained and the device is rendered simpler, less expensive and otherwise more convenient and advantageous for use, all as will be hereinafter more fully set forth.

The novel features of the invention will 35 hereinafter be definitely claimed.

In order that my invention may be the better understood, I will now proceed to describe the same with reference to the accompanying drawings, wherein—

Figure 1 is a view in elevation of a trunk constructed in accordance with an embodiment of my invention, one of the closure members being shown in open position; Fig.

45 2 is a sectional view taken substantially on the line 2—2 of Fig. 1; Fig. 3 is a fragmentary view in perspective of the rock shaft herein included and illustrating the hook member carried thereby; and Fig. 4 50 is a view in perspective of the spring jaws herein included together with a coacting lock.

As disclosed in the accompanying drawings, 55 1 denotes a cylindrical hollow body of predetermined dimensions and having one end open, and arranged within the body is

a concentric circular partition 2 which contacts with the side wall of the body to afford an annular chamber A into which is adapted to be placed a tire or tires such as employed in connection with automobiles. 60

The space confined by the circular partition 2 is intersected by the partition 3 affording the compartments B and C and the ends of said compartments adjacent the open 65 end of the body 1 are each partially closed by the fixed plate 4. By this arrangement it will be readily perceived that miscellaneous articles may be readily placed within the compartments B and C, the compartment 70 C being preferably intended for inner tubes or the like while the upper compartment B is particularly intended for use in connection with tools or similar objects.

Hingedly connected at diametrically opposed points to the free marginal portions of the side of the body 1, as indicated at 5, are the closure sections 6 and 7 substantially semi-circular in form but of such size as to have their straight marginal portions in overlying relation when the sections 75 are in closed position relative to the body 1.

Disposed along the inner face of the section 6 and in parallelism with the straight edge 8 thereof is a rock shaft 9 suitably held 80 to the section 6 through the medium of the bearing straps 10, and the opposite extremities of said shaft 9 are turned to afford the hook members 11 which, upon substantially a quarter turn being imparted to the shaft 90 9, are adapted to engage the keepers 12 carried by the side wall of the body 1 and disposed inwardly of the annular chamber A, said keepers 12 being diametrically opposed and occupying a plane at right angles to 95 the plane of the hinged connections 5 hereinafore referred to. As illustrated in the accompanying drawings, the keepers 12 comprise staple or loop members of conventional type. 100

The straight marginal portion of the section 6 is adapted to overlie the corresponding marginal portion of the section 7 so that when the hook members 11 are interlocked with the keepers 12, both of the sections 6 105 and 7 will be held in closed position.

Substantially midway its length the shaft 9 has affixed thereto through the medium of the set screw 14, a rock arm 15 which serves as a medium for imparting the requisite 110 rocking or rotary movement to the shaft 9, and the straight marginal portion of the sec-

tion 6 is provided with an open-ended slot 16 to permit the requisite movement being imparted to the rock arm 15. The straight marginal portion 17 of the section 7 is also provided with an open-ended slot 18 for a similar purpose.

5 The outer surface of the section 7 inwardly of and in alinement with the open-ended slot 18 has affixed thereto the plate 19 provided with the outstanding spring jaws 20 between which the free end portion of the rock arm 15 is adapted to be received when the rock shaft 9 has been adjusted to cause the hook member 11 to interlock with the keepers 12. The extremities of the jaws 20 are provided with the openings 21 so that a suitable lock L may be engaged with the jaws in order to prevent the closure sections 6 and 7 being opened by an unauthorized 10 person or to prevent accidental opening of said sections.

15 From the foregoing description, it is thought to be obvious that a trunk constructed in accordance with my invention is of an extremely simple and comparatively inexpensive nature and is particularly well adapted for use by reason of the convenience and facility with which it may be assembled, and it will also be obvious that my invention 20 is susceptible of some change and modification without material departure from the principles and spirit thereof and for this reason I do not wish to be understood as limiting myself to the precise arrangement 25 and formation of the several parts herein 30 35

shown in carrying out my invention in practice, except as hereinafter claimed.

I claim:—

A trunk of the class described comprising a hollow body having one end open, an annular partition within the body concentric to the axial center of the body and coacting with the side walls of the body to afford a chamber, a partition dividing the space confined by the annular partition and affording additional compartments, closure members hinged to the opposite side portions of the body at points substantially longitudinally alined with the second named partition, adjacent margins of said members overlapping when the members are in closed adjustment, said adjacent margins being provided with recesses adapted to register when in overlying relation to afford a slot, a locking member carried by the inner face of the closure member which overlies the second closure member, said locking member coacting with the side walls of the body for maintaining the closure members in closed position, and an operating arm for the locking member extending exteriorly of the trunk through the slot afforded by the registering openings of the closure members when in overlapping relation.

40 45 50 55 60 65 In testimony whereof I hereunto affix my signature in the presence of two witnesses.

EDWARD C. ROSS.
